ABSTRACT OF THE DISCLOSURE

There is disclosed a base plate having in one side a groove constituting a track for toy vehicles. A coil spring rotatably fitted into the groove and engageable by the catch member or driver depending from a toy vehicle drives the engaged vehicle along the track when the spring is rotated by some suitable driving device such as a small electric motor. The cross-sectional peripheral outline of the track groove is such that the width of the mouth of the groove is narrower than the maximal diameter of the spring so that the same is safely held captive in the groove. There is also disclosed a method of producing the track groove in an economic fashion.

This invention relates to a method of producing play sets with toy vehicles, comprising a base provided with at least one track on which the toy vehicles may move, said vehicles being propelled by means of a rotatable screw or core spring, sunk into the track and engaged by means of catch elements depending from the toy vehicles.

In such toy vehicle sets, the screw springs are usually located in recessed grooves or slots in the base plates on which the tracks are formed. The screw springs must be given a good guidance in their grooves or slots so that they will remain in their position of use in spite of their continuous rotation changes in speed, and reversal. This is especially important at those points where the tracks curve. For this reason, the grooves accommodating the screw springs must not only open upwards, but must have only a narrow slot at the top relative to their internal diameter, through which the pin-like elements of the vehicles can engage said screw springs.

Difficulties are encountered when trying to satisfy these requirements, especially when the base plate, together with the tracks, grooves and other parts is to be produced from synthetic plastics materials by the deep-drawing method, in order to exploit the advantages inherent to both the plastics material and the method in question.

This problem is solved according to the present invention in that the plastics material base plate accommodating the track(s) is provided with slot-shaped recess for containing a screw spring which surrounds its screw spring by more than 180° and has an upwards-opening slot.

In the manufacture of a base plate of this kind for a toy vehicle set described at the outset, the process adopted will be preferably one wherein the plate is provided, for example in the course of deep-drawing, with a semi-cylindrical recess flanks of which project slightly above the plate surface, whereafter the upwardly-projecting end portions of the flanks are bent inwards towards one another, for instance by a pressing process, so as to leave free the aforementioned slot, through which the catch elements of the toy vehicles can extend.

The progress offered by the invention is, that the groove- or slot-shaped recesses are so formed for con-

2

taining the screw springs, that only a narrow, upwards opening slot is present, so that the springs cannot jump out of their seating, which they would tend to do when they are driven. Another advantage resides in that this form of the grooves or slots can be achieved without requiring additional components such as covering strips or the like, which would have to be made separately, to be fastened subsequently to the base plate.

It is of course possible to have the pressing process, in the course of which the elevated wall portions of the grooves are bent inwardly, follow immediately the drawing process during which the base plates are shaped.

The accompanying drawing illustrates the invention schematically, with reference to an exemplary embodiment.

FIG. 1 shows a top view of a base plate, provided only with an oval track, for a toy vehicle set;

FIG. 2 is a partial section on an enlarged scale, after completion of the drawing process; and

FIG. 3 shows the same partial section on an enlarged scale after completion of the pressing process.

The base plate *a*, which is advantageously formed from a sheet of plastics material by deep drawing for example, has in the example of embodiment here shown only an oval track, in the center of which a recessed slot *b* is located, accommodating a screw spring *c*, which is rotatable by some suitable means, e.g. a miniature electric motor and which thereby entrains a driver projecting thereinto from the toy vehicles, said drivers being formed in the usual manner as thin pins.

As already mentioned, the screw spring tends to jump out of its slot in upward direction, if the aperture of the latter corresponds to its internal diameter. The risk of the screw springs leaving their grooves arises especially when the direction of travel is reversed, or when the rotational speed of the spring is changed. For this reason, the slot must have an opening in the form of a narrow slot *d*.

This is achieved according to the invention by forming during the deep drawing of the base plate *a*, the slot-shaped recess *e* so that its flanks *f* project above the plane of the base plate, thus forming upward-projecting end portions or lips *g* extending along the slots.

These end-portions *g* of the flanks *f* are then bent inwards towards one another in a pressing process following the deep drawing, so that they assume the position shown in FIG. 3, that is, they are located approximately in the plane of the base plate *a*.

They leave between them the aperture of the slot *d*, through which the driver pins of the vehicles can project downwards. The driving screw-spring *c* is thus surrounded by more than 180° by the wall of the recess in which it is located.

I claim:

1. A method of producing a base plate having in one of its sides a track groove for toy vehicles into which groove a coil spring is rotatably fitted for driving a vehicle engaged with the spring by rotating the same, said method comprising the steps:

forming in a base plate an elongate groove having along its longitudinal edges upwardly protruding lips; inserting into said groove a coil spring freely rotatable therein and having a diameter less than the maximal depth of the groove; and

turning said lips inwardly across the mouth of the groove to reduce the width of the mouth to a width less than the diameter of the coil spring thereby holding the same captive in the groove.

2. In the method according to claim 1 the steps of initially forming said groove with a semi-spherical cross-sectional outline at its base upwardly continued by straight wall portions into said protruding lips, and then turning

said lips and the contiguous straight wall portions into a configuration such that the final peripheral cross-sectional outline of the groove is substantially circular and the lips are flush with said side of the base plate.

3. In the method according to claim 1 the step of forming said base plate of thermo-plastic material as a one-piece structure.
